FIG. 1.

12 2 15

10 13

FIG. 3.

INVENTOR.
Albert M. Ahern.
By Martin Smith apply

UNITED STATES PATENT OFFICE.

ALBERT M. AHERN, OF SANTA MONICA, CALIFORNIA.

DISHWASHING DEVICE.

Application filed July 6, 1927. Serial No. 203,742.

My invention relates to a dish washing device and has for its principal object the provision of a relatively simple, practical and inexpensive device that may be connected to 5 a faucet or the like, and which device may be advantageously employed for the purpose of washing dishes that are placed in a sink or other suitable container.

Further objects of my invention are to 10 provide a dish washing device that may be manipulated without the necessity for placing the hands in the washing fluids; further to provide a device of the character referred to with a perforated container for soap or the like, and which latter is mixed with the water 15 passing through the device, thereby producing soapsuds for the purpose of cleansing the dishes; and further to provide a dish washing device that includes a readily detachable 20 brush that serves as a scrubbing element while the device is in use.

With the foregoing and other objects in view, my invention consists in certain novel 25 features of construction and arrangement of parts that will hereafter be more fully described and claimed and illustrated in the accompanying drawing, in which—

Fig. 1 is a perspective view of a dish washing device constructed in accordance with my 30 invention.

Fig. 2 is an enlarged vertical section taken on the line 2—2 of Fig. 1.

Fig. 3 is a vertical section taken on the line 3—3 of Fig. 2.

Referring by numerals to the accompanying drawings 10 designates a container preferably formed of sheet metal, the lower end of which is closed by an integral plate 11, and the upper end being provided with a readily 35 removable cap or cover 12 and which latter may be firmly secured on the container preferably by means of pins 13 that are seated in the wall of the container and which are adapted to engage in bayonet slots 14.

Secured to and projected outwardly from the rear side of the container is a handle 15, and projecting outwardly from the upper portion of the front side of the container is a short tube 16 to which may be connected 40 one end of a flexible tube or hose 17.

The opposite end of this flexible tube or 45 hose may be connected in any suitable manner to a faucet or the like, and which latter is associated with a suitable source of heated water supply.

Extending through the lower portion of the container 10 and secured to the wall thereof is a rod 18, the ends of which project a slight distance outwardly from the wall of the container, thereby providing supports 60 and points of attachment for a brush that is positioned beneath the container.

The brush utilized on my improved dish washing device comprises a frame that is preferably formed of two pieces of wire 65 twisted together and said frame being shaped so as to form a pair of parallel members 19, each of which carries a field or body of radially arranged bristles 20, thus forming a pair of substantial cylindrical brushes which, when the brush frame is applied to the container, lie immediately beneath the bottom of the container as illustrated in Figs. 2 and 3.

The end portions of the twisted wire brush frame are extended upward to form substantially inverted V-shaped members 21, the upper ends thereof being bent to form half round loops 22, which when the brush frame is applied to the inside of the container are sprung into position over the projecting ends of the rod 18, thereby retaining the brush in proper position beneath the container.

Formed through the bottom of the container and extending across the central portion thereof are two or more rows of small apertures 23, which latter are for the purpose of permitting soap treated water to pass from the container on to the bristle body of the brush while the device is in service.

Loosely arranged within the container 10 is a smaller container 24, preferably a small can formed of sheet metal and having a removable cap or cover 25 and the wall of this small container is perforated. This container 24 is adapted to receive soap or like detergent, and the size of this soap container is such that it rests on the rod 18 as illustrated for Fig. 2.

By virtue of this arrangement the soap container is held above the bottom 11 of the container 10, and thus the entire series of apertures 23 are always open to permit the escape of soap treated water.

In the use of my improved dish washing device hot water from a faucet or other suitable source of supply is permitted to pass through a flexible tube 17, and this heated water fills the container 10, and acting upon the soap or detergent contained in the can 24 produces soapsuds, and which latter dis-

charges through the apertures 23 on to the cylindrical brushes that are positioned beneath the bottom of the container.

The device is manipulated by manually engaging the handle 15 and moving the brush portion of the device over the surfaces of the dishes or other articles to be cleansed, and the scraping and scrubbing action of the brushes together with the flow of soap treated water 10 or soapsuds very rapidly and efficiently cleanses the same.

The heated water flowing through the container 10 and the movement of the device while in service, agitates the soap container 15 24 so as to produce the desired degree of soapsuds that passes from the container on to the cylindrical brush body.

When desired the brush frame may be readily removed from the container by applying sufficient outward pressure to one of the end portions 21 of said frame to disengage the loop at the upper end of said end portion from the corresponding end of the rod 18.

Thus it will be seen that I have provided 25 a dish washing device that is relatively simple in construction, inexpensive of manufacture, capable of being readily manipulated without the necessity for placing the hands in the dish washing water, and which device 30 is very effective in performing the functions for which it is intended.

It will be understood that minor changes in the size, form and construction of the various parts of my improved dish washing device 35 may be made and substituted for those herein shown and described without departing from the spirit of my invention, the scope of which is set forth in the appended claims.

I claim as my invention:

40 1. In a dish washing device, a container provided with a perforated bottom, a rod secured to and passing through the lower portion of the body of said container, the ends of which rod project outwardly from the body 45 of the container and a brush carrying frame

positioned beneath the bottom of the container with its end detachably mounted on the projecting ends of the said rod.

2. In a dish washing device, a container provided with a perforated bottom, a cover 50 detachably arranged on the upper end of said container, a rod secured to and passing through the lower portion of the body of the said container, the ends of which rod project outwardly from the body of the container, a 55 resilient brush carrying frame positioned beneath the bottom of the container and the ends of said resilient frame being formed into loops that are detachably mounted on the projecting ends of the said rod.

3. In a dish washing device, a container provided with a perforated bottom, a cover 60 detachably arranged on the upper end of said container, a rod secured to and passing through the lower portion of the body of the said container, the ends of which rod project outwardly from the body of the container, a 65 resilient brush carrying frame positioned beneath the bottom of the container and the ends of which resilient frame are bent upwardly and formed into inverted V-shaped portions that are detachably mounted on the projecting ends of the said rod.

4. In a dish washing device, a container provided with a perforated bottom, a rod secured to and passing through the lower portion of the body of the said container, the ends of which rod project outwardly from the body of the container, a brush carrying frame positioned beneath the bottom of the container with its ends bent into inverted V-shaped portions that are detachably mounted on the projecting ends of the said rod, the upper end portion of said container being 70 provided with a water inlet opening and a removable cover for the top of said first mentioned container.

In testimony whereof I affix my signature.

ALBERT M. AHERN.
